UNITED STATES PATENT OFFICE.

BERT VICTOR, OF PASCAGOULA, MISSISSIPPI

REINFORCED-CONCRETE SHEET-PILE.

1,083,570.

Specification of Letters Patent.

Patented Jan. 6, 1914.

Application filed January 14, 1913. Serial No. 741,993.

To all whom it may concern:

Be it known that I, BERT VICTOR, a citizen of the United States of America, residing at Pascagoula, in the county of 5 Jackson and State of Mississippi, have invented certain new and useful Improvements in Reinforced-Concrete Sheet-Piles, of which the following is a specification, reference being had therein to the accompanying drawing.

This invention relates to an improved type of pile which is to be used principally in constructing sea walls and the like.

One of the objects of the invention is to provide a sea wall which is formed from a series of piles having interlocking joints, the tongue of each of the piles being provided with a longitudinally extending groove, thus leaving an opening between 15 the piles so that water may be forced between the piles.

Another object of the invention is to provide an improved type of coping for the sea wall which assists in holding the piles together.

Another object of the invention is to provide an improved type of mold for forming the piles.

Another object of the invention is to provide an improved type of device for holding the piles close together while sinking them into position.

With these and other objects in view this invention consists of certain novel combinations, constructions, and arrangements of parts as will be hereinafter fully described and claimed.

In the accompanying drawings:—Figure 1 is a side elevation of one of the piles. Fig. 40 2 is an edge elevation of the piles shown in Fig. 1. Fig. 3 is a vertical sectional view through one of the piles. Fig. 4 is a transverse sectional view through one of the piles. Fig. 5 is a top plan view of a section of the 45 wall before the coping is put in place. Fig. 6 is a top plan view of the mold showing one of the piles being formed. Fig. 7 is a perspective view of one end portion of the mold. Fig. 8 is a perspective view of the device for holding the piles close together while sinking them. Fig. 9 is a side elevation showing the sea wall in the process of construction. Fig. 10 is a perspective view of a section of the complete sea wall.

Referring to the accompanying drawings it will be seen that this invention comprises

a sea wall formed from a plurality of piles 10, each of which is rectangular in cross section as shown in Fig. 1, and provided with a longitudinally extending groove 11 having a curved inner end. A tongue 12 extends from the opposite side of the pile and is positioned in alinement with the groove 11 so that the tongue 12 will fit into the groove of an adjoining pile. This tongue 12 is provided with a longitudinally extending groove 13 leaving an opening 14 between the tongue 12 and the inner end of the groove 11 to permit a stream of water to be forced down, thus keeping the tongue and groove 70 free from sand and mud when sinking the pile. This opening is not for sinking the pile, the pile being sunk from a stream of water from the outside. The lower end of the pile is inclined as shown at 15 so that when the pile is sunk the inclined end will cause it to be crowded against the adjacent pile and thus a tight joint formed between the two piles. Each of these piles is formed from a concrete mixture which is poured 80 into a mold shown in Figs. 6 and 7 and allowed to remain there until set. The mold comprises a flooring 16 which is secured to the supporting bars 17 so that the flooring will be slightly elevated, thus permitting it 85 to be easily handled.

The side walls 18 and 19 are formed from sheet metal strips which are bent longitudinally to form the upper and lower flanges 20 and 21. The lower flanges 20 fit between 90 cleats 22 and may if desired be secured to the flooring by any suitable means, although this is not necessary since the weight of the cement in the mold will hold the side walls in a vertical position. These walls are 95 crimped intermediate their height to form the ribs 23 and 24, the rib 23 forming the groove 11 and the rib 24 forming the tongue 12. It should be noted that the rib 24 is crimped to form the rib 25 which forms the 100 groove 13. These side walls are set up and are connected at their upper edges by the cross bars 26 having bent ends 27 extending over the edges of the flanges 21, thus preventing the side walls from being spread 105 apart by the weight of the concrete. A suitable board 28 is placed at one end of the mold and a diagonal board 29 is placed in the mold according to the length at which it is desired to have the pile. If desired reinforcing rods 30, 31, and 32 may be provided in order that the piles will be rein-

forced, and thus prevented from being cracked or broken.

When constructing the sea wall the piles are sunk into the ground one after the other with the tongues 12 fitting into the grooves 11. While one of the piles is being sunk into the ground it is held tightly against the adjacent pile by the device shown in Fig. 8. This device comprises a shaft 33 having arms 34 with which links 35 are pivotally connected. These links are provided with eyes 36 through which pins are passed, the pins fitting into openings 37 formed in the piles at points above the level of the ground. The rollers 38 which are mounted upon the shaft 33 are forced against the pile being sunk by the handle 39. Thus, from an inspection of Fig. 9 it will be seen that by forcing the handle downwardly that the rollers will be forced against the pile, thus pressing the pile tightly against the pile already in position and thus causing the tongue 12 to fit tightly in the groove 11.

The reinforcing bars 31 extend above the upper ends of the piles and are formed into eyes 40 through which a rod 41 is passed. It will thus be seen that the piles are connected by the rod 41 and that, therefore, when the coping 42 is molded in the upper

ends of the piles that the piles will be connected together, thus forming a solid sea wall. This coping is molded in sections of about 50 feet long with small spaces left between the sections of the coping so that expansion and contraction will be permitted without danger of the sea wall being damaged.

Having thus described the invention what is claimed as new, is:

A wall comprising a plurality of piles, a plurality of bracing rods embedded in each of said piles and having their upper ends extending beyond said piles and terminating in eyes, a reinforcing rod extending longitudinally of said wall and passing through the eyes of said first mentioned reinforced rods, and a coping molded upon the upper ends of said piles and connecting said piles to form a continuous coping around the edge of said wall, the upper portions of said first mentioned rods and said second mentioned rod reinforcing said coping.

In testimony whereof I hereunto affix my signature in presence of two witnesses.

BIRT VICTOR.
